Coloplast A/S; Nick Baumann

(57) **CLAIM**

The ornamental design for a debridement sponge, as shown and described.

DESCRIPTION

FIG. 1 is a front plan view of a debridement sponge;
FIG. 2 is a back plan view of the debridement sponge illustrated in FIG. 1;

FIG. 3 is a bottom side view of the debridement sponge illustrated in FIG. 1, with the front of the debridement sponge oriented up;

FIG. 4 is a left side view of the debridement sponge illustrated in FIG. 1, the right side view is a mirror image thereof; and,

FIG. 5 is a top side view of the debridement sponge illustrated in FIG. 1, with the front of the debridement sponge oriented down.

1 Claim, 5 Drawing Sheets
